(57) **CLAIM**

The ornamental design for a multipack beverage container
insulation system, as shown and described.

DESCRIPTION

FIG. 1 is a perspective view of the multipack beverage
container insulation system;

FIG. 2 is a front side view I of the multipack beverage
container insulation system;

FIG. 3 is a rear side view of the multipack beverage
container insulation system;

FIG. 4 is a first end view of the multipack beverage container
insulation system;

FIG. 5 is a top view of the multipack beverage container
insulation system;

FIG. 6 is a bottom view of the multipack beverage container
insulation system; and,

FIG. 7 is a perspective view of a second end of the multipack
beverage container insulation system.

The broken lines illustrate stitching of the multipack beverage
container insulation system and forms no part of the
claimed design.

1 Claim, 6 Drawing Sheets
